G. J. Max. of Wallingford, Conn.
Letters Patent No. 1651, dated Aug. 19, 1862.

——————

Mar. 1651

The schedule referred to in these Letters Patent and making part of the same.

Be it known that I, G. J. Mix, of Wallingford, in the County of New Haven and State of Connecticut, have invented a new and useful Design for the form of Spoons Shanks; and I do hereby declare that the following is a full, clear and exact description of the same, reference being had to the accompanying drawings forming part of this specification, in which

Figures 1. and 3. are plan views,

Figure 2. is a cross sectional view of the shank.

Whereas others skilled in the art to make my invention I will proceed to describe it.

The form of the bowl A. and handle B. is the same as that of ordinary spoons.

The shank C. is made convex in its central part, as shown at a, each side of this convex part is flanked by a flat rib b. and the edges of the ribs are bevelled as shown at c.

Spoons having convex shanks are already known, and this convexity I do not claim.

But having thus described my invention, what I claim as new and desire to secure by Letters Patent, is -

The design for the form of a spoon shank, which consists in having the convex part a. flanked by the flat ribs b. b. and the bevelled edges c. c. as herein shown and described.
